UNITED STATES PATENT OFFICE.

JOHN J. SCHWOB, OF ST. LOUIS, MISSOURI.

ELEVATOR.

SPECIFICATION forming part of Letters Patent No. 761,011, dated May 24, 1904.

Application filed February 23, 1904. Serial No. 194,916. (No model.)

To all whom it may concern:

Be it known that I, JOHN J. SCHWOB, a citizen of the United States, residing at St. Louis, State of Missouri, have invented certain new and useful Improvements in Elevators, of which the following is a specification containing a full, clear, and exact description, reference being had to the accompanying drawings, forming a part hereof.

10 My invention relates to elevators; and it consists of the novel features herein shown, described, and claimed.

In the drawings, Figure 1 is a detail showing the bulkhead and elevator-collar in section and the first floor in elevation, parts being broken away to economize space. Fig. 2 is a horizontal section on the line 2 2 of Fig. 1. Fig. 3 is a section on the line 3 3 of Fig. 1. Fig. 4 is a horizontal section on the line 20 4 4 of Fig. 1.

Referring to the drawings in detail, the lower end of the elevator-shaft terminates in an air-tight bulkhead 5, set in masonry 6, embedded in the ground. An air-pipe 7 leads 25 from the lower end of the bulkhead 6 upwardly to a convenient position, and an intake-valve 8 and an adjustable blow-off valve 9 are fixed upon the upper end of the pipe 7.

The bottom 10 of the elevator-car may be 30 constructed of wood, and a metal plate 11 is placed against the bottom 10, said plate being held in position by the metallic binding-sections 12 and 13, said sections being in the form of a channel-bar in cross-section, each 35 section forming half a square in plan.

The bulkhead 6 is slightly larger than the outer faces of the sections 12 and 13, thus leaving the air-space 14 between the bulkhead and the car, so as to allow the air to pass 40 readily to a limited extent either to or from the space between the floor of the car and the bottom of the bulkhead. The lower ends of the runners 15 extend to the bottom of the bulkhead, and their inner faces have the cut-away portions 16, said cut-away portions being wedge-shaped and extending from near the top of the bulkhead about two-thirds of the way to the bottom of the bulkhead and 45 said cut-away portions being widest at their upper ends, so as to form spaces between the

inner faces of the runners and the bottom of the car through which the air may escape from below the car as the car descends into the bulkhead, said spaces constantly decreasing in size as the car goes down. Notches 55 are formed in the bottom of the car to receive the full size of the runners 15. Posts 17 extend upwardly from the bottom 10, and the guide-clips 18 are secured to these posts and embrace the runners to hold the car in its 60 vertical position.

Supposing that the car is in the bottom of the bulkhead and is to be elevated, air will pass into the bulkhead through the intake-valve 8 and through the air-space 14 around 65 the bottom of the car, and as the car passes to the upper part of the bulkhead additional air will pass through the cut-away portions 16 of the runners. The upper end 19 of the bulkhead is flared outward. Should the cable 70 break or the car fall for any reason, a compressed-air cushion will be formed within the bulkhead, and as the car descends into the bulkhead and the air-pressure is greatly increased air will pass outwardly from the blow-off valve 9 and upwardly through the cut-away portions 75 16 of the runners and through the space 14 around the bottom of the car. As the car continues to descend into the bulkhead the cut-away portions 16 become smaller 80 and smaller, thus reducing the space through which the air can escape until the car nears the bottom of the bulkhead, and these spaces are reduced to a minimum. Then the air can escape only through the blow-off valve 9 and 85 through the space 14 and the car will settle down easily into the bulkhead.

A trap-door 20 is provided in the roof of the car, through which the operator may climb out of the car after the car has passed 90 into the bulkhead.

I claim—

1. In an elevator, the combination with an elevator-shaft of an air-tight bulkhead extending downwardly from the shaft; runners extending to the bottom of the bulkhead, there being wedge-shaped cut-away portions at the inner faces of said runners, the widest part of said cut-away portions being near the top of the bulkhead; an outlet-pipe leading from 95 100

the bulkhead; an inlet-valve and blow-off valve connected to said outlet-pipe; and an elevator-car adapted to engage said runners and descend into the bulkhead, there being a 5 metallic binding around the floor of the car and leaving a slight air-space between the binding and the wall of the bulkhead, substantially as specified.

2. In an elevator; the air-tight bulkhead 5
10 at the lower end of the elevator-shaft; the elevator-car adapted to descend into the bulkhead and having the bottom 10; the metallic plate 11 placed against the bottom; the metallic binding-sections 12 and 13 applied to
15 the edges of the bottom so as to form a slight air-space between said binding-sections and the inner face of the bulkhead; an outlet-pipe leading from the bottom of the bulkhead; an intake-valve connected to the outlet-pipe; and
20 a blow-off valve connected to the outlet-pipe; substantially as specified.

3. In an elevator; an air-tight bulkhead 5 set in masonry and embedded in the ground at the lower end of the elevator-shaft; the runners 15 extending to the bottom of the 25 bulkhead and having the cut-away portions 16 at their inner faces and beginning near the upper end of the bulkhead, said cut-away portions decreasing downwardly, the bottom edge of the elevator-car having notches to receive 30 the runners; and the metallic binding-sections 12 and 13 applied to the edges of the bottom 10 and leaving a slight air-space between the bottom and the inner face of the bulkhead, substantially as specified.

In testimony whereof I have signed my name to this specification in presence of two subscribing witnesses.

JOHN J. SCHWOB.
